UNITED STATES PATENT OFFICE.

JOHN BROADFOOT, OF GLASGOW, SCOTLAND.

IMPROVEMENT IN WASH-BASINS.

Specification forming part of Letters Patent No. **133,405**, dated November 26, 1872.

To all whom it may concern:

Be it known that I, JOHN BROADFOOT, of Glasgow, in the county of Lanark and Kingdom of Scotland, have invented certain Improvements in Lavatories, of which the following is a specification:

Nature and Objects of the Invention.

My said invention relates to lavatories, designed more particularly for passenger-ships, but also suitable for dwelling-houses and other situations; and its object is to combine convenience, usefulness, ornament, and economy in first cost.

Description of the Drawing.

Figure 1 is a vertical transverse section of a lavatory embodying my invention, as fitted in a ship's state-room. Fig. 2 is a front elevation of the same.

General Description.

A is a hollow support or stand for the lavatory-top or basin-piece B, into which the used water is allowed to pass through a plug-hole, C, in the bottom of the basin, and which is fitted with a tap, D, at the bottom for withdrawing such used water periodically. The basin-piece B may be earthenware or enameled metal, and the support A may be of cast-iron, zinc, or other metal, or of earthenware. The

support A, as here shown, is made in the form of an ornamental bracket, and is fixed to the bulkhead partition or lining E by screws F, some of which can be entered from the inside, while lugs may be formed on the hollow support, as at G.

The lavatory can thus be easily fixed in position or removed, as circumstances may require, without involving the tedious and expensive joiner's work unavoidable with ordinary wooden lavatory-fittings.

Having thus particularly described my said invention and the manner in which the same is to be applied, what I claim is—

The hollow support or bracket A, having the basin B set in the top, provided with a discharging-plug, C, the said support forming a receptacle for the discharge from the said basin, and provided with a draw-off plug, D, the whole constructed to be attached to the wall, in the manner described.

In testimony whereof I, the said JOHN BROADFOOT, have hereunto set my hand the 27th day of December, in the year of our Lord one thousand eight hundred and seventy-one.

JOHN BROADFOOT.

Witnesses:
